FAUCET

Harold W. Fowler, Oakland, Calif.

Application June 13, 1934, Serial No. 730,381

1 Claim. (Cl. 251—134)

The invention relates to faucets and particularly those which are especially constructed for relatively small and portable installations such as commonly used in automobile service stations for filling radiators.

An object of the invention is to provide a faucet of the character described wherein the fluid pressure of the supply line as well as the fluid flow is directed against the rear of the faucet valve in a manner urging the latter in all of its positions to a seated, passage closing position.

Another object of the invention is to provide a faucet of the above character having an outline especially formed to comfortably nest within the hand of the operator and with the valve actuating means of the faucet incorporated in said outline for ready gripping.

A still further object of the invention is to provide a faucet of the character described wherein the valve operating lever is particularly arranged to afford both convenience in grasping and an improved leverage advantage on the valve parts.

Yet another object of the invention is to provide a faucet of the above character which is simply and sturdily constructed of a minimum number of parts and is arranged to permit of ready dismembering for quick adjustment or replacement of worn parts.

The invention possesses other objects and features of advantage, some of which, with the foregoing, will be set forth in the following description of the preferred form of the invention which is illustrated in the drawing accompanying and forming a part of the specification. It is to be understood, however, that variations in the showing made by the said drawing and description may be adopted within the scope of the invention as set forth in the claim.

Referring to said drawing:

40 Figure 1 is a side elevation with a portion of the faucet shown in section to illustrate the valve assembly.

Figure 2 is an elevational view showing the protective covering for the faucet, which covering is broken away and shown in section.

Figure 3 is an enlarged fragmentary sectional view of the valve assembly.

With reference to the drawing, the faucet 6 of my invention comprises a body portion 7 to which is connected a discharge nozzle 8 and a pivoted actuating lever 9. The body 7 itself is especially formed for ready engagement by the hand of the user and to this end includes a cylindrical portion 11 which is arranged to nest in the palm of the hand and which joins with an enlarged offset

portion 12 which is adapted to engage in the crotch of the hand between the thumb and index finger. This arrangement leaves the fingers of the hand free for gripping the actuating lever 9 which is for such engagement extended into a generally parallel, spaced relation with respect to the body portion 11.

Extending approximately centrally through the body portion 11 and 12 are passageways 13 and 14 which are interconnected at their adjacent ends and provide for the passage of fluid through the body portion of the faucet. In the present instance the passage 13 houses the valve mechanism and is formed with an annular valve seat 16 against which is arranged to move into passage 15 closing position a valve 17. In accordance with my invention the valve mechanism provides for the use of a standard tire chuck washer 18 for the valve proper and which is supported in a cupped receptacle 19 for longitudinal movement in the passage 13 to and from the seat 16. As an important feature of my arrangement, the fluid flow through the passage 13 is in the direction of a valve closing movement so that such flow and the pressure drop through the valve will urge the valve to a seated passage closing position. Entrance of the fluid to the passage in this manner may be conveniently effected by connecting the fluid supply main to the outer end 21 of the passage 13 which for such connection may be enlarged and tapped as here shown. In order, however, to insure a proper closing of the valve, regardless of the conditions of flow or pressure in the passage 13, I prefer to include in the assembly a valve closing spring 22. As here shown this spring is mounted and compressed between the receptacle 19 and a hollow plug 23 threadably carried in the passage 13 adjacent the outer end 21. If desired, a screen 24 may be incorporated in the plug as here shown for filtering the fluid.

Means for displacing the valve from its seat against the action of the fluid pressure and for admitting fluid into the passage 14 here include an actuating stem 26 which is slidably carried in a bore 27 formed in the enlarged body portion 12. As may be best seen in Figure 1, the bore 27 is provided in substantially axial alignment with the passage 13 and the stem 26 is extended therethrough and through the adjoining portions of the passages 13 and 14 to directly engage the valve assembly. In order that the engagement of the valve means and the displacement thereof by the stem shall not incur any wear on the relatively soft valve washer and as may be best seen in Figure 3, the end 28 of the stem is engaged

in an intermediate coupling member 29 which is extended centrally through the washer and fitted into a socket 30 formed in the washer receptacle 19. Preferably an enlarged shoulder portion 31 is provided on the member 29 for holding the washer against release from the receptacle 19 when the valve is in open position. Leakage of fluid from the passage 14 through the bore 27 is here prevented by a packing ring 32 and a retaining plug 33 mounted about the stem 26 in an enlarged outer portion 34 of the bore 27.

Since the stem may be readily slipped from engagement with the coupling member 29, it will be understood that replacement or adjustment of the valve washer may be quickly and readily effected by removing the plug 23 and slipping the valve parts from the outer end of the passage 13 without in any way disturbing the valve stem. However, should it be advisable for any reason to also remove the stem, the same may be slipped from the packing means and likewise removed from the outer end of the passage 13. Thus, with the exception of the packing means, the entire valve assembly may be quickly and easily mounted or removed either jointly or by parts from the outer end of the passage 13.

With the valve in closed position the stem 26 is arranged to extend with the outer end 35 thereof projected outwardly from the packing plug 30 and the outer side 36 of the body portion 12 for engagement with and displacement by the actuating lever 9. Since the axis of the stem is generally parallel to the axis of the cylindrical body portion 11, the lever 9 is pivoted for movement of a portion 37 thereof against and in the direction of displacement of the stem. As here shown the lever is pivoted adjacent an end 38 thereof in an outstanding yoke 40 formed on the body side 36 and disposed with the portion 37 extending at substantially right angles to the axis of the stem and provided with a substantially right-angularly extending portion 39 which is arranged to overlie the cylindrical portion 11 for grasping and drawing to the body 11 for actuation of the valve. It will be noted that by reason of the closeness of the pivotal connection of the lever and stem as compared to the length of the lever engaged for actuation, the mechanical advantage afforded by the lever enables the use of a relatively strong valve closing spring while providing for a smooth and easy operation of the lever.

In the present embodiment the discharge nozzle or tube 8 is threadably engaged in the body portion 12 and extends through the side 36 thereof into communication with the passageway 14. As particularly here provided the tube 8 extends from the side 36 immediately adjacent the yoke

40 to normally engage the end 38 of the lever and to in this manner limit the latter's movement from the body and to maintain the lever in position for ready grasping. The discharge end of the tube is preferably provided with a right angular bend portion 41 which may, as here shown, be inclined slightly in the direction of the handle. As will be understood, the portion 41 will be normally disposed as shown in the drawing, in the plane of the body portion and lever, but may by 10 reason of its threaded connection in the body be readily adjusted to other angular positions. In this regard it will be noted that the shape of the body portion permits of ready grasping by the fingers and engagement of the lever either in the 15 crotch between the thumb and index finger or by the thumb alone where a reversal of the tube portion 41 is desired.

If desired, the outstanding portions of the faucet, such as the body and discharge tube may be 20 provided with a rubber coating 42 as here shown in Figure 2 to afford a cushioning means for protecting the faucet parts against shock.

I claim:

In a faucet of the character described, a body 25 including an elongated portion and a transversely offset portion each having a passage therethrough joined at the inner end thereof with the other passage, a discharge conduit carried by said offset portion in communication with the passage 30 therein and extending from said body in parallel relation to said elongated portion, the outer end of said first passage being arranged for connection to a source of fluid and formed adjacent the inner end thereof with an annular valve seat, a 35 valve mounted in said last mentioned passage for movement to and from a passage closing position engaging said seat and being urged to said position under the action of the fluid pressure and flow from said source, a spring mounted in said 40 last mentioned passage for assisting in the movement of the valve into engagement with said seat, an actuating stem slidably carried in said offset portion in spaced relation to said conduit and in substantially axially aligned position with said 45 valve and arranged to engage and displace the valve from closed position against the action of the spring and the fluid therebehind, and a lever pivoted to said offset portion intermediate said 50 conduit and stem and having a portion thereof extended at substantially right angles to and arranged to engage and displace said stem and an angular portion extended into spaced and generally parallel relation to said elongated portion, the end of said lever being arranged to engage 55 said conduit and limit the outward movement thereof from the body.

HAROLD W. FOWLER.
